UNITED STATES PATENT OFFICE.

JOHN R. RUECKERT AND ROBERT A. HALL, OF BALTIMORE, MARYLAND.

FAUCET.

SPECIFICATION forming part of Letters Patent No. 288,865, dated November 20, 1883.

Application filed August 10, 1883. (No model.)

To all whom it may concern:

Be it known that we, JOHN R. RUECKERT and ROBERT A. HALL, both of the city of Baltimore and State of Maryland, have invented 5 certain Improvements in Faucets, of which the following is a specification.

To fully understand the nature of our improvement it must be remembered that after turning the key of a faucet to stop the flow of 10 liquid the portion of the barrel between the key and the outlet or discharge end retains its contents for a considerable period of time, or until air has an opportunity to pass to the head of the suspended column of liquid and counterbalance the pressure of the atmosphere acting 15 on the other end of the column.

The object of this invention is therefore to overcome this difficulty by constructing a faucet with means to admit air rapidly to the upper 20 end of the suspended column upon the closing of the key, as will hereinafter fully appear.

In the accompanying drawings, forming a part hereof, Figure I is a longitudinal section 25 of the improved faucet closed. Fig. II is a similar view of a portion of the faucet, also closed, but showing the key in a reverse position. Fig. III is a partly sectional view of portions of the faucet as they would appear 30 when the said faucet is open.

Similar letters of reference indicate similar parts in all the views.

A is the barrel, and B the key of the faucet. The portion of the barrel which in ordinary 35 faucets retains liquid for some time after the key is closed is denoted by a. The discharge opening in the key is represented by b, and c

is an air-channel leading from the upper part of the key to a cross-opening, d, in the same. The opening d is at a right angle with the liquid-discharge opening b, and is located some distance above it. The portion a of the barrel is enlarged at its inner end to bring it in communication with the cross air-opening d in the key B.

By referring to Figs. I and II it will be seen that air passing through the aperture c communicates with the interior of the portion a of the barrel in either position that the key may be placed to cut off the flow of liquid. In Fig. 50 III the key is in such position as to allow a discharge of liquid, the opening b being in a line with and forming a portion of the passage in the barrel. When the faucet is open, as shown in Fig. III, both ends of the cross 55 air-opening d are stopped.

We are aware that faucets having their discharge through the lower end of the key have been constructed so as to admit air to the interior of the key, and this construction we dis- 60 claim; but

We claim as our invention—

In a faucet, the key thereof closed at its lower end and provided with a controllable opening to admit air, when the key is closed, to the portion of the barrel between the key and the discharge end of the barrel, substantially as and for the purpose specified.

JOHN R. RUECKERT.
ROBERT A. HALL.
